UNITED STATES PATENT OFFICE.

GEORGE F. ABENDSCHEIN, OF RUTHERFORD, NEW JERSEY, ASSIGNOR TO THE STAIB-ABENDSCHEIN COMPANY, OF NEW YORK, N. Y., A CORPORATION OF NEW YORK.

HAMMER-RAIL SPRING.

Application filed August 29, 1922. Serial No. 584,937.

To all whom it may concern:

Be it known that I, GEORGE F. ABENDSCHEIN, a citizen of the United States of America, residing at Rutherford, in the county of Bergen and State of New Jersey, have invented certain new and useful Improvements in Hammer-Rail Springs, of which the following is a full, clear, and exact description.

10 The present invention is an improvement primarily applicable to grand pianos and will be hereinafter described as used in this connection. It resides in a means for counter-balancing and counteracting the 15 weight and inertia of the hammer lifting rail in these and similar pianos.

In all pianos to which the improvement is applicable, the hammers are lifted by a rail to vary the amplitude of their stroke 20 upon the strings to soften or modify the tone. This rail is operated in ordinary pianos by means of a foot pedal while in automatic pianos it is moved by a pneumatic electric or other mechanism controlled by the 25 music sheet or the hand of the player to give the required expression. In any event, the weight and inertia of the rail and the hammers lifted thereby are considerable and the force for overcoming them is such as to require, in the one case, sensible muscular effort 30 and, in the other, special mechanism capable of exerting the proper power. This fact detracts from the delicacy of operation and may add very materially to the cost of the 35 apparatus or appliances used.

The object of my invention is to so counteract or counterbalance the weight of the lifting rail and its load, that no sensible amount of force or power is required for its 40 movement and this I have accomplished by the use of bow springs, one end adjustably attached to a stationary part of the piano or piano action and the other to the lifting rail. I have found it desirable to use two of such 45 springs for a rail and to attach them to the ends of the rail, but others may be used if space be afforded for them and the requirements of particular instruments demand it.

These springs are so designed as to exert 50 their full lifting or supporting effect uniformly over a wide range of movement and they are of such character that their effect may be readily and easily adjusted with great nicety by varying their length. Their construction and arrangement will be under-

stood from an examination of the drawings annexed and the detailed description which follows.

In the said drawings—

Fig. 1 is a side view in elevation of that 60 part of a grand piano action to which my improvement is applicable, showing the parts in their normal position.

Fig. 2 is a similar view showing the same parts but with the rail and hammers raised. 65

Fig. 3 is a perspective view of the bow springs showing the manner in which they are attached.

Fig. 4 is a detail section on line 4—4 of Fig. 2 of the means for adjusting the 70 springs.

The mechanism of a grand or similar piano which comprises the lifting hammer rail is well known in the art and I have therefore shown only such parts of the mechanism as are required to illustrate the nature 75 and manner of applying my improvement. These parts are as described below.

1 is the lifting rail which is carried by rods 2, pivoted at 3. The means for raising 80 the rods and rail are designated by the numeral 4 and may be of any desired and proper character operated by a foot pedal, pneumatic or otherwise. The hammers 5 are shown in dotted lines. 85

A support rail 6 is secured to the piano frame and carries pads 7 upon which the rail 1 rests. Bow springs 8, which may be composed of lengths of steel piano wire, are secured at one end to the support rail 6 and 90 at the other to the lifting rail. The attachment to the support rail is so made that the effective length of the springs may be readily varied, to secure the necessary lifting force of the springs upon the hammer rail. 95 For this purpose I pass the ends of the springs through perforations in said support rail and secure them by screws 9 which may be loosened to permit adjustment of the effective length of the wires. 100

The connection between the springs and the lifting rail may be of any kind, but to compensate for the movement of the points of attachment and to the fixed lengths of the supporting rods 2. I prefer 105 to secure eyes 11 to the rail and to connect the turned up ends of the springs thereto by means of rings or links 10.

From the above description of the improvement it will now be seen that the 110

5 springs have numerous and important functions and advantages. It, or they if more than one be used, permit the swinging hammer-rail of a regular grand piano action or an action known as a lost motion grand piano action installed either in a hand played instrument or in a player grand piano however operated, that is by 10 foot, electric or any other power, to be lifted with a less expenditure of energy without regard to the manner in which such energy is developed whether by foot power through the pedal mechanism, by the pneumatic bellows and player action 15 or otherwise.

20 By the use of my improvement it also follows that the lifting hammer rail is held always in well balanced suspension, under precise control from its normal or 25 any other point of rest, passing through all points covering both extremes of the velocity of its movement. It is delicately responsive at any point in its path of movement to the lifting power however 30 this may be applied. The proper fulfillment of the functions and purpose of the improvement are in large measure dependent upon the character of the spring or springs employed. It is manifest, for example, that many forms of spring might 35 be used which would be wholly incapable of accomplishing the desired results.

What I therefore claim as my invention is—

35 1. In a piano action, the combination

40 with the hammer lifting rail of one or more springs secured to a stationary part of the piano and to the lifting rail, said springs being of the kind which is capable of exerting a uniform supporting and counter-balancing influence on said lifting rail throughout its entire range of movement.

45 2. In a piano action, the combination with the hammer lifting rail of a bow spring, one end connected to a stationary support in the piano and the other to the lifting rail, said spring being of the form which is capable of exerting a uniform supporting or counter-balancing influence on 50 said rail throughout its entire range of movement.

55 3. In a piano action, the combination with the hammer lifting rail of steel bow springs connected at one end to a stationary support-rail in the piano, by means whereby the point of such connection may be varied in order to vary the effective length and lifting force of the springs and at the other end to the said lifting rail as herein described.

60 4. In a piano action, the combination with the hammer lifting rail of steel bow springs connected adjustably at one end to a stationary support in the piano, and at the other end to said lifting rail, and swinging links intermediate such ends and the lifting rail, as herein set forth.

65 In testimony whereof I hereto affix my signature.

GEORGE FREDERICK ABENDSCHEIN.
